CARL F. LUNDEBERG, OF HARTFORD, CONNECTICUT, ASSIGNOR TO UNDERWOOD TYPE-WRITER COMPANY, OF NEW YORK, N. Y., A CORPORATION OF DELAWARE.

CARD CURVING AND STRAIGHTENING DEVICE.

1,150,608.

Specification of Letters Patent.

Patented Aug. 17, 1915.

Application filed December 26, 1911. Serial No. 667,595.

To all whom it may concern:

Be it known that I, CARL F. LUNDEBERG, a citizen of the United States, residing in Hartford, in the county of Hartford and 5 State of Connecticut, have invented certain new and useful Improvements in Card Curving and Straightening Devices, of which the following is a specification.

This invention relates to means for curving cards to conform to the curvature of the platens of typewriting machines, and also for straightening the cards after they have been written upon.

It has been customary to place the card in 15 the typewriting machine in a flat condition, and owing to the stiffness of the cards, it was impossible to get the same to fit or cling close to the platen; consequently the card, when struck by the types, not having a substantial backing, would present a blurred typewritten effect.

An object of my invention is to overcome this difficulty by providing a simple, efficient and practical machine to curve the 25 cards, and again straighten them.

I provide a device that will curl or curve a card or thick paper, preparatory to placing it in a typewriter, so that the card will conform substantially to the cylindrical periphery of 30 the platen. The same device is also adapted for straightening the card again after it has been typewritten.

Other objects and advantages will herein-after appear.

35 In the accompanying drawings, Figure 1 is a perspective view showing a machine constructed in accordance with my invention and showing a card in position partly curled. Fig. 2 is an end view, showing the 40 gearing driving the curving rolls. Fig. 3 is an enlarged transverse section through the machine, illustrating the card in the act of being curled. Fig. 4 is a view similar to Fig. 3, showing the machine reversed and in the 45 operation of straightening a written card. Fig. 5 is an enlarged section of the curving rolls, showing corrugations which may grip the cards to carry them forward.

The card curling mechanism is mounted 50 on a stand, box or table 1 which may form a receptacle for a stack of cards 14. Fixed to the stand 1 at opposite sides thereof are upright brackets 2 which form a support for a horizontal curling roll 3. Said roll ex-

tends across the front edge of the stand and 55 has secured in its ends bearing pins 12^a which are journaled in the brackets 2. A swinging carrier 11 comprises end plates 11^a and 11^b pivoted on the pins 12^a, and brace rods 22 and 30 connecting said plates. 60 The rod 22 extends through curved slots 23, which have their center of curvature in the pins 12^a, and permits a limited swinging movement of the carrier 11 about the axle of the roll 3 as an axis.

A second curling roll 6 is supported at its ends by swinging arms 8 and 9 respectively connected to the carrier 11 by pivots 10. The downward movement of the arms 8 and 9 is limited by stop pins 31, the arms being 70 yieldingly held against said pins by springs 12. Said downward movement is permitted by the slots or enlarged openings 6^a in plates 11, through which the gudgeons of the roll 6 pass. A hand crank 4 is secured to one end 75 of the roll 3, and at the opposite end of said roll is secured a spur gear wheel 5 in mesh with a pinion 33 fixed to the axle of the roll 6.

A curved guard 17 is located directly 80 above the roll 6, and is secured at its ends to the plates 11^a, 11^b. A stationary inclined table 15 extends lengthwise of the rolls and is secured at its ends to the brackets 2, the lower edge of the table being in proximity 85 to the rolls. The surfaces of the rolls 3 and 6 are preferably corrugated or roughened to prevent slipping of the cards as they are fed between the rolls. The carrier 11 is adapted to be held in either of the positions shown 90 in Figs. 3 and 4 by means of a locking pin 19 engaging recesses or openings 20 (Fig. 2) in the bracket 2.

When the machine is to be used for curling a card, the carrier 11 is swung to the 95 position shown in Fig. 3, and held by the locking pin 19. When the carrier is in such position, the roll 6 is directly over a block 34 having its upper surface 13 curved to conform to the periphery of the roll 6, said 100 curved surface and the opposing surface of the roll forming an arc-shaped slot or passage through which the card is guided.

The card 14 to be curved is placed on the table and the crank 4 turned to feed the 105 card between the rolls. As it passes between the roll 6 and the surface 13, it is curved as shown in Fig. 3, the curvature being sub-

stantially the same as the surface of the typewriter platen on which the card is to be placed.

As the card is fed through the rolls, the 5 curved end passes upward over the guard 17 and around as indicated by the dotted lines, Fig. 3. As the end of the card moves downward after passing over the guard 17, it may touch the flat portion of the card and 10 also the roll 6, but the curvature of the card causes it to ride over the roll and along the inner face of the guard 17.

To straighten the card after it has been written upon, the carrier 11 is swung to the 15 position shown in Fig. 4, the pin 19 engaging an opening 20 to hold it in such position. This movement of the carrier carries the roll 6 away from the curved surface 13 and into close proximity to the lower edge 20 of the table 15. The curved card is now placed on the table 15 with its convex surface upward, and the lower edge of the card is passed between the roll 6 and the edge of the table 15 and fed forward between the 25 two rolls. As the card is held close to the roll 6 by the edge of the table, the portion of the card between the said edge and bite of the rolls, is held in contact with the curved surface of the roll 6 and thereby 30 curved or deflected in the reverse direction sufficiently to counteract the original curvature and cause the card to be fed upon the table 1 substantially flat.

Variations may be resorted to within the 35 scope of the invention, and portions of the improvements may be used without others.

Having now described my invention, I claim:

1. In a card curling machine, the combination of a guide, a support, a swinging carrier mounted on said support, a roll mounted resiliently upon and with respect to said swinging carrier and a roll co-operating with said resiliently mounted roll.

45 2. In a card curling machine, the combination of a guide, a support, a swinging carrier movable to either of two defined positions, a resiliently mounted arm on said carrier, and a roll supported by said arm.

50 3. In a card curling machine, the combination of a guide, a support, a swinging carrier, a resiliently mounted roll, a second roll having an axle journaled in said support, and arms supporting said first roll in contact with said second roll.

55 4. In a card curling machine, the combination of a guide, a support, a roll, a swinging carrier, a second roll having an axle journaled in said support, arms supporting said first roll, a pivot for each of said arms, and springs to hold said first roll in contact with said second roll.

60 5. In a card curling machine, the combination of a guide, a support, a roll, a swinging carrier, a second roll having an axle

journaled in said support, arms supporting said first roll, a pivot for each of said arms, springs to hold said first rolls in contact with said second roll, and gears for driving said roll in a feeding direction.

6. In a card curling machine, the combination of a guide, a support, a corrugated roll, a swinging carrier, a second corrugated roll having an axle journaled in said support, arms supporting said first roll, a pivot for each of said arms, springs to hold said first roll in contact with said second roll, and gears for driving said rolls in a feeding direction.

7. In a card curling machine, the combination of a support, two rolls approximately in contact, means for rotating said rolls, said rolls being movable into either of two positions, a table coincident with the common tangent of the said rolls in one position, and a table extending at an angle to said common tangent, said tables forming part of said support.

8. In a card curling machine, the combination of a guide, a support therefor, a swinging carrier mounted on said support and movable to either of two defined positions, card-bending rolls, a table, and means for holding said carrier at an angle to the table.

9. In a card curling machine, the combination of a guide, a support provided with recesses, a swinging carrier, card bending rolls mounted on said carrier, said rolls being approximately in contact, a table, and means for holding said carrier so that the common tangent of the rolls forms an angle with the table, said means comprising a pin on the carrier adapted to engage in one of the recesses in said support.

10. In a card-curling machine, the combination of a card guide, a support, a series of recesses in said support, a carrier mounted to swing on said support, card bending rolls mounted on said carrier, and a table arranged to direct, in one position of the carrier, a card directly to the bite of the rolls, and in another position of the carrier, to direct a card obliquely to said bite.

11. In a card curling machine, the combination of a guide, a support, a swinging carrier, card curling rolls, a table, means for holding said carrier at an angle to said table, said means comprising a pin to engage recesses in said support, and a bar for arresting said carrier in its plurality of positions.

12. In a card-curling machine, the combination of a support, a carrier mounted to swing on said support, a pair of rolls mounted in said support, and a bar having its top surface concaved to correspond with the outer surface of one of said rolls, the said roll being adapted to be brought into substantial coincidence with said concaved sur-

- face, in one position of said swinging carrier.
13. In a card curling machine, the combination of a support, a carrier mounted on said support, a pair of rotating rolls approximately in contact mounted on said carrier, means for holding said carrier in any one of several positions on said support, and a bar having a surface concaved 5 on substantially the radius of one of said rolls, and in which said roll practically nests when the swinging carrier is in one position.
14. In a card curling machine, the combination of a support, a carrier mounted to swing on said support, a pair of rotating rolls mounted on said carrier, a bar having a surface concaved to substantially the radius of one of said rolls, means whereby the 10 carrier may be swung and held with said roll nesting in the recess in said bar, a box in connection therewith, and a guard for said rolls.
15. In a card curling machine, the combination of a support, a carrier mounted to swing on said support, a pair of rotating rolls mounted on said carrier, a bar having a surface concaved to substantially the radius of one of said rolls, means whereby the 15 carrier may be swung and held with said roll nesting in the recess in said bar, a box in connection therewith, said box comprising a flat for receiving cards, and a guard for said rolls.
16. In a card curling machine, the combination of a support, a carrier mounted on said support, said carrier being adapted to oscillate, a pair of rolls rotating approximately in contact mounted on said carrier, 20 an inclined table mounted on said support, and in one position of said carrier making an acute angle with the common tangent of said rolls, and a receiving table.
17. In a card curling machine, the combination of a support, a carrier mounted on said support, said carrier being adapted to oscillate, a pair of rolls rotating approximately in contact mounted on said carrier, an inclined table mounted on said support, 25 and in one position of said carrier making an acute angle with the common tangent of said rolls, a receiving table, and a curved shield around the exterior of which a card curled by the action of the rolls may be guided.
18. In a card curling machine, the combination with two coöperating rolls, means whereby a card may be fed between said rolls, a carrier for said rolls, means whereby the angle of the carrier with respect to the feeding means may be changed, and a concaved bar opposite one of said rolls.
19. In a card curling machine, the combination of coöperating rolls, a carrier therefor, said carrier being adapted to oscillate 30
- means to feed a card between said rolls, and means to hold a portion of the card directly against the curved surface of a roll and thereby curve the card.
20. In a card curling machine, the combination of rolls, a bar having a curved surface forming with one of the rolls a curved passage for the card, means to rotate said rolls and feed a card between the rolls and through said passage and means whereby 70 said rolls may be swung to another position to straighten the card.
21. In a card curling machine, the combination of parallel rolls, means to feed a card between said rolls, a bar having a curved 75 guiding surface opposite one of the rolls and forming a passage therewith and in position to deflect or curve the card after passing through the rolls and means whereby said rolls may be swung to another position 80 to straighten the card.
22. In a card curling machine, the combination of curling rolls, means coöperating therewith to curve a card, and mechanism coöperating with the rolls to straighten the 85 card.
23. In a card curling machine, the combination of rolls, means to feed the card between said rolls, mechanism coöperating with the rolls to curl the card, and mechanism operable to flatten the card when fed 90 a second time between said rolls.
24. In a card curling machine, the combination of a curling roll, means coöperating therewith to curl a flat card, and means coöperating with said roll whereby to again 95 flatten the card.
25. In a card curling machine, the combination of rolls between which the card is adapted to be fed, means located beyond the 100 bite of the rolls to curve or curl a card as it is passed through said rolls, and means upon the opposite side of the said bite and coöperating with said rolls to flatten the curved card.
26. In a card curling machine, the combination of a pair of rolls between which the card is adapted to be fed, means coöperating with one of said rolls to curve the card 105 as it passes beyond the rolls, and means coöperating with one of said rolls to flatten the card when again fed through the rolls.
27. In a card curling machine, the combination of a pair of feed rolls, means to operate the rolls, and card curling and flattening devices located on opposite sides of 110 said rolls.
28. In a card curling machine, the combination of a roll, a swinging carrier mounted to swing about said roll as an axis, a second roll supported by said carrier, means coöperating with said second roll to curve a card when the carrier is in one position, and means to flatten the card when the carrier 115 is in another position.
- 120
- 125
- 130

29. In a card curling machine, the combination of a curling roll, a swinging carrier for said roll, a curling device coöperating with the roll when the roll is in one position, 5 a straightening device coöperating with the roll when the roll is in another position and a second roll coöperating with said roll.

30. The combination of a pair of coöperating rolls, a carrier for one of said rolls 10 mounted to swing about the axis of the other roll, a curved block forming with the swinging roll a curved passage when said roll is in one position, and means for guiding a card or the like over a portion of the periphery 15 of the swinging roll when the latter is in another position.

31. In a card curling machine, the combination of a pair of feed rolls, an inclined 20 table located on one side of said rolls, and a curved block located on the opposite side of 25 said rolls and forming with one of the rolls a curved passage-way.

32. In a card curling machine, the combination of a pair of feed rolls, an inclined 25 table on one side of said rolls, and a curving block on the opposite side of said rolls, one 30 of said rolls being movable respectively into position to coöperate with the curving block to curve a card, and into position to co- operate with said table to flatten the card.

33. In a card curling machine, the combination of a roll, a stationary support in which said roll is journaled, a swinging carrier, a roll supported thereby and coöperating 35 with the first-named roll, a block having a curved surface located beneath the swinging roll to curve a card, a table coöoperating with the swinging roll to straighten the curved card, and means for holding the 40 swinging carrier in positions to cause the swinging roll to coöperate with the said block and table respectively.

34. In a machine for curling sheet material, the combination of a pair of feed 45 rolls substantially in contact, a support for said rolls, said rolls being movable into and out of position, and means to hold the sheet material in contact with one of the rolls for a limited distance after it passes the bite of 50 the rolls, said means being opposite said one of the rolls and forming between itself and said one of the rolls, a channel.

35. In a machine for curling sheet material, the combination of a pair of feed 55 rolls, devices on opposite sides of the bite of

said rolls to curve the sheet material about a portion of a roll, and means to move said roll into positions to coöperate alternately with said devices.

36. In a card-curling machine, the combination of a roll, a curved surface opposite and curved to correspond to said roll, and coöperating means to feed a card between said surface and roll, and thereby curl the card said rolls being movable into and out 65 of position.

37. In a card-curling machine, the combination with a block having a concaved upper surface, of a roller having a periphery substantially corresponding to the curve of the 70 said concaved surface and arranged close to said surface whereby the concaved surface and the roller form a passage through which a card may be fed to be bent, a second roller adapted to coöperate with the roller first 75 mentioned to feed a card into said passage in one position of said rollers, a swinging carrier on which said rollers are mounted, a coöperating feed table, and means for holding said rollers in one position near the 80 concave surface to curve a card and in another position near the feed table to straighten a card.

38. In a card curling machine, the combination of a pair of rollers forming a card 85 feeding mechanism, said rollers being mounted so as to be movable into one of two positions, a bar having a curved face co- operating with one of said rollers in one position to curl a card, and a table arranged 90 at an angle to the common tangent of said rollers when in the other position, and co- operating therewith to straighten a curled card.

39. In a card-curling machine, the combination of a pair of rolls provided with corrugated gripping surfaces, a frame, for carrying one of said rolls and oscillatable about the axis of the other of said rolls, whereby the distance between the axes of 100 the rolls remains substantially constant, a curved passageway through which a card may be fed, and means coöperating with said oscillatable roll, in one position to curve and in another to straighten a card.
